JAMES J. B. MC ELRATH, OF CENTRE, ALABAMA.

DATING AND STAMP-CANCELING MACHINE.

SPECIFICATION forming part of Letters Patent No. 520,698, dated May 29, 1894.

Application filed February 10, 1894. Serial No. 499,767. (No model.)

To all whom it may concern:

Be it known that I, JAMES J. B. MC ELRATH, of Centre, in the county of Cherokee and State of Alabama, have invented a new and useful 5 Improved Dating and Stamp Canceling Machine, of which the following is a full, clear, and exact description.

My invention relates to an improved power-operated device for the dating and simultaneous cancellation of the stamps on letters or packages, and has for its object to provide a novel, simple and efficient machine of the character indicated, which may be operated by foot-power or other means, and that will 15 rapidly and reliably date and cancel postage stamps on any desired number of letters, cards or packages that are successively fed to the machine.

To this end, my invention consists in the construction and combination of parts, as is hereinafter described and claimed.

Reference is to be had to the accompanying drawings, forming a part of this specification, in which similar figures of reference indicate 25 corresponding parts in all the views shown.

Figure 1 is a plan view of the device arranged to be operated by foot-power. Fig. 2 is a sectional side view, on the line 2—2 in Fig. 1. Fig. 3 is a side view opposite the arm 30 row 3 in Fig. 1. Fig. 4 is an enlarged, detached plan view of the printing and canceling roller that is a portion of the improvement; and Fig. 5 is a sectional side view, on the line 5—5 in Fig. 1.

There is a rectangular frame provided for the machine, composed of the similar side pieces 10, that are held spaced apart a proper distance by the bottom piece 11 and transverse bolts 12, the bolts being so arranged at 35 the ends and along the upper edges of the side boards intermediately of the ends, that room will be afforded for the working parts of the machine to be located between the frame sides. A column 13, is preferably employed as a support for the machine frame, and is secured thereto at one side near the longitudinal center, having such a proportionate height as will adapt it to sustain the working mechanism at a convenient elevation for easy operation by an attendant, as will be further explained.

An endless apron 14 is supported at each end by a rear cylindrical roller 15 and a

smaller forward cylindrical roller 16, these rollers slightly exceeding in length the width 55 of the apron. There is an equal space afforded between the ends of the apron rollers 15, 16, and the sides of the frame, the distance between said sides 10, being preferably made equal to twice the length of the rollers. There 60 is a journal shaft provided for each apron-supporting roller, which shafts 15^a, 16^a, are slightly longer than the frame is wide, and have their end portions journaled in the sides of said frame, as shown in Fig. 1. 65

The smaller apron roller 16, that is at the feeding end of the machine is located nearer the end of the frame than is the rear roller 15, and both of these rollers are placed at such a height from the bottom 11, that the 70 upper ply of the endless apron which is the working surface of the same, will be nearly in a horizontal plane.

A cylindrical feeding roller 17, is sustained in a plane parallel with the axis of the shaft 75 16^a, by a journal shaft 17^a, which has its end portions loosely engaged with boxes secured in the frame sides 10. The roller 17 is preferably given a greater diameter than that of the lower roller 16, the length of the rollers 80 being equal. A thick envelope 17^b, of felt, cloth or other available elastic material is secured upon the peripheral surface of the roller 17, and the complete roller is so located that its yielding envelope will touch the top 85 surface of the apron 14, near the front end of the latter.

Above the rear apron-supporting roller 15, a similar roller 18, is rotatively sustained by its shaft 18^a so that it will lie in a parallel 90 plane with the lower roller mentioned, its periphery being spring-pressed upon the rear end portion of the apron 14, by means of the vertically slidable boxes 18^b and springs 18^c, that occupy vertical slots in the side pieces 95 10 of the machine frame.

At a suitable distance from the pair of rear rollers 15, 18, a cylindrical roller 19, of a nearly equal diameter therewith is secured upon the axial shaft 19^a, that is journaled in the frame 100 sides 10, at such points as will permit the top surface of the roller 19 to have contact with the lower surface of the top ply of the endless apron 14, said roller being located between the two longitudinally-extending plies 105 of the apron, as shown in Figs. 2, 3 and 5.

In the same vertical and transverse plane with the roller 19, a printing roller 20 is revolubly supported by its axial shaft 20^a, that is furnished with boxes which slide in vertical slots formed in the sides 10, these boxes 20^b being spring-pressed upwardly. The periphery of the substantially cylindrical roller 20 is recessed at a suitable point between its ends, for the reception of a dating stamp 21, that is made to receive the necessary letters and figures as usual, said block being held in place by the adjustable screws 22, shown in Figs. 1 and 4. Another die-block 23 is provided, that is embedded in the body of the roller 20, and extends around a portion of the same, having a corresponding degree of curvature lengthwise, so as to adapt its outer side to form a peripheral face for the roller, said die block being held in place by screws 24. The dating stamp 21 and die block 23, are similarly projected above the general surface of the roller they are embedded in, and the latter named piece has its curved outer surface longitudinally grooved 25 at proper distances apart, thus providing a series of canceling ribs on said surface, as indicated in Fig. 4, which ribs are extended from the dating stamp a suitable length for effective service.

Above the printing roller 20, an inking roller 25 is rotatably supported by its center shaft 25^a, that is slidably journaled in the frame sides 10, by a loose engagement of the box bearings 25^b, with vertical slots in said sides, the lowest depression of these boxes allowing the contour of the roller 25, to have contact with the dating stamp 21 and die block 23, the depressed surface of the printing roller avoiding the face of the inking roller; and to 30 elastically enforce the impinge of the inking roller on the parts it touches, springs are located in the slots of the frame above the boxes 25^b, which springs press the boxes downwardly. The rollers 19 and 20 are made of 35 sufficient length to project their ends beyond each side edge of the apron 14, and on the top roller 20, a circumferential flange 20^c is formed near each terminal, which flanges are of a proper and equal width and depth to 40 adapt them to have pressure on the lower roller 19.

Between the pair of rollers 19, 20, and forward rollers 15, 18, two cylindrical rollers 26, 27, of an equal diameter are located, one above 45 and the other below the top ply of the apron 14. These rollers are preferably made of a less diameter than the inking roller, and are rotatably maintained in position so that their adjacent portions will have contact with the 50 top ply of the apron 14, by their shafts 26^a, 27^a. The lower roller 27, is arranged to reciprocate vertically a limited distance, by the provision of boxes for its journals, which boxes loosely engage vertical slots formed in 55 the frame pieces 10, and are seated on springs that are also located in the frame slots just mentioned, as shown at 27^b, in Fig. 3.

The shaft 19^a is extended outside of the frame pieces 10, sufficiently to each side of the machine to permit the grooved pulley 19^b to be secured on one end above the column 13, and the larger grooved pulley 19^c to be affixed on the same end of the shaft 19^a, outside of the pulley 19^b. There is a grooved band wheel 13^a mounted to rotate on the side 70 of the column 13, by a journal stud 13^b, that projects from the latter, a band 13^c being extended between and over said band wheel and the grooved pulley 19^b, the band wheel being equipped with a crank arm and treadle of ordinary form for its rotatable movement, as shown in Figs. 1, 4 and 5.

An end portion of the roller shaft 17^a is extended from the frame of the machine on the side that is connected to the column 13, and 85 on this shaft end a small grooved pulley 17^c is placed and secured in the same vertical plane with the pulley 19^c, to which it is connected by the band 17^d, which band is crossed, as indicated by dotted lines in Figs. 3 and 5. 90 One end of the shaft 15^a is outwardly projected from one side of the frame, a grooved pulley 15^c being secured on the projected end of said shaft in alignment with a pulley 19^d on the shaft 19^a to which pulley it is connected by the band 15^d.

Each end of the shaft 27^a is projected beyond the sides 10, sufficiently to receive the two similar arms 27^e that are thereto secured so as to project toward the roller 19. The 100 arms 27^e are pivoted upon the frame pieces 10, so as to vibrate from a horizontal position, and have their outer ends lapped upon and pivoted to the adjacent ends of the upright links 27^d. From the end portions of 105 the shaft 20^a, that supports the printing roller 20, two levers 20^f are projected toward the roller 26, these levers being pivoted upon the frame sides 10 at 20^e, and upon the upper ends of the links 27^d at their outer ends, the 110 pivot points 20^e being located an equal and suitable distance from the shaft 20^a.

At the front of the machine, a feeding chute plate 10^b is affixed upon the end wall 10^c of the frame that extends below the chute plate 115 for its support, the plate is given any required width and length, and is slightly inclined inwardly and downwardly so as to project its inner end near to the front of the apron 14, and below the feeding roller 17. 120 The band 13^c that connects the wheel 13^a with the grooved pulley 19^b, rotates the latter in the same direction as the band wheel, and as the wheel 19^d is on the opposite end of the shaft 19^a, and is flexibly connected with the 125 shaft 15^a, whereon the rear roller 15 is secured, it will be seen that a rearwardly progressive movement of the upper ply of the apron, or in the direction of the arrow 4, will be produced when the band wheel 13^a is rotated in the direction of the curved arrow 1, 130 shown in Fig. 5. The band connection 17^d between the shaft 17^a and shaft 19^a being crossed, the direction of rotary motion trans-

Between the pair of rollers 19, 20, and forward rollers 15, 18, two cylindrical rollers 26, 27, of an equal diameter are located, one above and the other below the top ply of the apron 14. These rollers are preferably made of a less diameter than the inking roller, and are rotatably maintained in position so that their adjacent portions will have contact with the top ply of the apron 14, by their shafts 26^a, 27^a. The lower roller 27, is arranged to reciprocate vertically a limited distance, by the provision of boxes for its journals, which boxes loosely engage vertical slots formed in the frame pieces 10, and are seated on springs that are also located in the frame slots just mentioned, as shown at 27^b, in Fig. 3.

mitted from the latter named shaft is reversed, and the feeding roller 17 will be revolved toward the apron 14, or in the direction of the arrow 2, in Fig. 5.

5 By the peculiar arrangement of the arms 27^c, links 27^d, and levers 20^d, the roller shaft 27^a is adapted when depressed, to force the printing roller in the same direction against the stress of the springs that sustain the boxes 10^b, so that the introduction of material between the roller 26 and the upper surface of the apron 14, will cause the printing roller 20, to more forcibly impinge its end flanges 20^c, upon the lower roller 19, to receive rotary motion therefrom in the direction of the curved arrow shown opposite its end in Figs. 3 and 5.

In use, the operator arranges any desired number of letters, postal cards, or other mailable matter that is within the capacity of the 20 machine, upon the chute plate 10^b, the several pieces being piled one upon the other, and to facilitate the proper stamping and cancellation of the mail matter, letters or cards should be presented to the roller 17 with the end first 25 that has postage stamps on it, the printing roller at the start of work being adjusted so that the cancelling ribs of the die 23 will be in the position shown in Fig. 5, when the letters are engaged by it.

30 It will be seen that when a letter or postal card from the pile on the chute plate 10^b is shoved so that the rotating roller 17 presses it upon said plate and transfers it to the apron 14, the introduction of the letter or card so 35 compresses the elastic envelope 17^b as to insure the forward movement of the engaged piece, the lower roller 16 contributing to such a result. Before the rollers 16, 17, release the letter, it is shoved between the transfer rollers 26, 27, that in turn press the moving letter 40 upon the traveling apron 14, so that the end of the letter or card, without retardation, will be introduced between the apron and the printing roller 20, the roller 19 serving to prevent the apron from sagging at the point of 45 contact. As the canceling die is in position to engage the postage stamp or stamps on the letter when the latter is presented below the roller 20, and has previously been brought into 50 contact with the inking roller 25, it will be evident that as the letter moves along beneath the printing roller, the postage stamps on it will first be canceled, and then the dating stamp 21 will have contact with the face of 55 the letter near its longitudinal center, thereby imprinting the designating characters it carries, upon the letter in a distinct manner. As it is desirable in order to simplify the machine, that the printing roller 20, be allowed to move 60 continuously, it will be evident that on long letters or packages, the date stamp and canceling marks will be duplicated, which is not considered objectionable. By continuation 65 of the treadle movement, the letter that has been stamped and canceled, will be progressively moved until the discharging rollers 15, 18, grip its end, and as these are pressed to-

gether by the springs 18^c, it will be seen that the mail matter passed successively through the machine, will be properly date marked, 70 receive the mark of the post office location, and have all the postage stamps reliably canceled. When the mail matter is discharged from the machine it is caught at the rear by the box-like space afforded at the rear end of 75 the frame, and from there can be conveniently transferred to the assorting tables or into mail bags as may be required.

The roller 16, as shown, will drive the apron 14, faster than the periphery of the printing 80 roller 20, travels; if this should prove objectionable, the roller 16 may be increased in diameter to alter the travel of the apron and make it correspond with the speed of the printing roller.

85 It is evident that the machine may be readily arranged to receive power from a moving mechanical motor, by providing belts or gearing and dispense with foot power, also that other means of support than the column 13 90 may be provided if preferred.

It is claimed for this improved date stamp and canceling machine that it is simple, not liable to get out of working order, inexpensive to construct, and reliable in operation, and 95 that it is adapted to receive and operate upon letters or thin cards in equally as effective a manner as it will on thicker packages.

Having thus fully described my invention, I claim as new and desire to secure by Letters 100 Patent—

1. The combination, with the frame, the supported movable endless apron, the feeding roller at one end of the apron, two transfer rollers spaced from the feeding roller and embracing the top ply of the apron, the lower transfer roller being upwardly actuated, and a rotatable slidingly-supported printing roller above an apron supporting roller, both spaced from the transfer rollers, of a motion transmitting device connecting the lower transfer roller with the printing roller, which will depress said printing roller when the lower transfer roller is depressed, substantially as described.

115 2. The combination with the frame, the supported and movable endless apron, the feeding roller at one end of the apron, two transfer rollers spaced from the feeding roller and embracing the top ply of the apron, the lower transfer roller being spring-supported, and a spring-supported printing roller above an apron-supporting roller, both spaced from the transfer rollers, of a set of arms, links and levers arranged between the lower transfer roller and the printing roller and adapted to correspondingly depress the printing roller when the lower transfer roller is depressed, substantially as described.
